UNITED STATES PATENT OFFICE.

GEORGE P. ABORN, OF BROOKLINE, MASSACHUSETTS, ASSIGNOR TO BLAKE & KNOWLES
STEAM PUMP WORKS, A CORPORATION OF NEW JERSEY.

ENGINE-VALVE.

1,177,588.

Specification of Letters Patent.

Patented Apr. 4, 1916.

Application filed July 3, 1913. Serial No. 777,155.

To all whom it may concern:

Be it known that I, GEORGE P. ABORN, a citizen of the United States, residing at Brookline, county of Norfolk and State of Massachusetts, have invented certain new and useful Improvements in Engine-Valves, fully described and represented in the following specification and the accompanying drawings, forming a part of the same.

10 This invention relates to valve gear for steam pumps or other fluid engines and more particularly to cut-off mechanism embodied in such valve gear.

15 The objects of the invention include a more simplified mechanism equipped with a cut-off gear whereby greater economy in the use of steam or other motive fluid is made possible.

20 While the invention may be utilized in many forms of fluid engines, it is here illustrated in connection with a steam pump having a fluid actuated valve gear of a well known type.

25 In the drawings, Figure 1 is a sectional elevation taken longitudinally through the main and auxiliary steam cylinders on line 1—1 of Fig. 2, Fig. 2 is a sectional elevation taken on the line 2—2 of Fig. 1, Fig. 3 is a sectional plan taken on the line 3—3 of Fig. 1, Fig. 4 is a plan of the valve seat for the main slide valve, and Fig. 5 is a plan of 30 the main slide valve.

35 The main steam cylinder is indicated at 10, the piston 11 and the integral valve seat at 12. The main inlet ports in the valve seat are shown at 13 and 14 and the exhaust at 15. Bleeder ports, forming a second set of inlet ports, 16 and 17 are also formed in the valve seat and communicate by respective 40 passages with the main inlet ports by short channels as indicated at 18 in Fig. 2. The bleeder channels are controlled by hand valves 19 and 20.

45 The main slide valve 21, shown in Figs. 1 and 5, is a D valve of the Allen or Trick type, this form being preferred as it effects the cut-off with a minimum of travel. The valve is divided laterally into two sections, lettered *a* and *b* in Fig. 5. Section *a* cooperates with the main ports 13, 14, 15, and is provided with lap to close the ports early in the stroke and effect a cut-off of the steam. Section *b* cooperates with the bleeder ports, and having no lap, as shown, forms the full stroke valve, these ports, 16 and 17, being

open successively to the steam pressure during the full stroke or approximately the full stroke of piston 11.

It will be noticed that if the valves 19 and 20 are closed steam is admitted to cylinder 60 10 only through the *a* section of the valve, and the engine operates with the expansion of steam; if the valves 19 and 20 are opened, the steam passes through the bleeder ports and passages 18 to the main inlet ports, 65 thereby supplying steam to cylinder 10 throughout the full stroke or approximately the full stroke of piston 11. The valve 21 is equipped with a stem 22 which passes through a yoke 23 and connects at its upper 70 end with the auxiliary piston 24 located in auxiliary steam cylinder 25. The yoke 23 is moved by a balanced valve rod 26 and the proportions of the yoke and stem are such that there is a certain amount of lost motion 75 between them. The yoke carries at one side the auxiliary slide valve 27 which cooperates with an auxiliary valve seat located at one side of the cylinder 25, as best shown in Fig. 2. This valve seat is provided with admission ports 28 and 29 and exhaust ports 30, 80 31 and 32, the latter three ports communicating with the exhaust port 33 located as shown in Figs. 2 and 4.

85 The described mechanism operates as follows:—Assuming the parts to be in the position shown in Fig. 1, steam will pass through inlet 34 (Fig. 2) into chamber 35 and up through opening 36 into the auxiliary cylinder and into port 13 past the 90 right hand edge of main valve 21 and also through the port 37 in the main valve. The piston 11 will move to the left and steam will exhaust through port 14, under valve 21, and port 15.

95 At a predetermined point in the travel of main piston 11, the usual valve actuating gear (not shown) will engage the valve rod 26 and move it toward the right, carrying with it the yoke 23 and auxiliary valve 27. 100 The movement of the auxiliary valve to the right first uncovers steam port 28 and closes exhaust port 30, admitting steam at the left of the auxiliary piston through port 38 which balances the auxiliary piston as 105 ports 29 and 39 are open to steam at the opposite end.

110 As soon as the auxiliary piston is balanced, the yoke 23 will come into contact with the stem 22 of the main valve and the

continued movement of the yoke will carry the valve to the right. Less than a sixth of the total travel of the main valve will close the port 13 and thus shutting off the supply of steam from the piston 11, the stroke of which will be completed by the expansion of the steam previously admitted to the cylinder.

Just before the main valve 21 reaches its central position, the auxiliary valve 27 will have moved far enough to open exhaust port 32 and close steam port 29, and the auxiliary piston now being unbalanced will be driven over to the right, stopping when the right end of the auxiliary piston has closed the exhaust port 40, causing the piston to cushion on the steam confined between its end and the auxiliary cylinder head. The main valve 21 will now be in position for the return stroke of the main piston 11.

As previously described, if it be desired to have the steam follow full stroke, the bleeder valves 19 and 20 are opened, admitting steam to the main ports 13 and 14 independently of the action of the cut-off arrangement, this admission being controlled by the $\frac{1}{6}$ section of the main valve 21.

While the main valve 21 is shown as double ported for the purpose of reducing its travel, it is to be understood that the invention is not to be limited to this particular type of valve, it being obvious that an ordinary single ported valve, if made with sufficient lap and given the necessary travel could be made to accomplish the same results as regards the cut-off and its co-operation with the other parts of the valve.

What is claimed:

1. In combination, a main valve having a cut-off lap, a piston connected with said main valve to move it, a cylinder in which said piston is located, a valve chest for said main valve interposed between said cylinder and the seat for the said main valve, an auxiliary valve located in said valve chest and co-operating with said main valve to mechanically move the latter and to permit the main valve to be moved by its piston independently of said auxiliary valve and co-operating with a valve seat having ports connecting said valve chest with said cylinder, means to operate said auxiliary valve,

55
inder, means to operate said auxiliary valve, and means independent of the main valve for controlling the steam admission for full stroke.

2. In combination, a main valve having both an extended and a normal lap for early and late closing of steam admission, a piston connected with said main valve to move it, a cylinder in which said piston is located, 60 a valve chest for said main valve interposed between said cylinder and the seat for the said main valve, an auxiliary valve located in said valve chest and co-operating with said main valve to mechanically move the latter and to permit the main valve to be moved by its piston independently of said auxiliary valve and 65 co-operating with a valve seat having ports connecting said valve chest with said cylinder, and means to operate said auxiliary valve.

3. In combination, a main valve having both an extended and a normal lap for early and late closing of steam admission, a transverse stem for the main valve, a piston connected with the stem and adapted to move the main valve, a cylinder in which said piston is located, a valve chest for said main valve interposed between said cylinder and the seat for the main valve, an auxiliary 75 valve located in said valve chest, the said auxiliary valve being equipped with a yoke surrounding the stem of the main valve and having lost motion relative thereto, whereby the auxiliary valve and its yoke are 80 adapted to co-operate with said main valve to mechanically move the latter and to permit the main valve to be moved by its piston independently of said auxiliary valve and its yoke, the auxiliary valve further co-operating with a valve seat having ports connecting said valve chest with said cylinder, and means to operate said auxiliary valve.

90
In testimony whereof, I have hereunto set my hand, in the presence of two subscribing witnesses.

GEORGE P. ABORN.
